UNITED STATES PATENT OFFICE.

SAMUEL HOAR, OF VIRGINIA, MINNESOTA.

TUNNELING-MACHINE.

1,162,607.

Specification of Letters Patent. Patented Nov. 30, 1915.

Application filed January 20, 1915. Serial No. 3,285.

To all whom it may concern:

Be it known that I, SAMUEL HOAR, a citizen of the United States, residing at Virginia, in the county of St. Louis and State of Minnesota, have invented certain new and useful Improvements in Tunneling-Machines, of which the following is a specification; reference being had therein to the accompanying drawing.

10 My invention relates to improvements in tunneling machines.

The object of my invention is to provide a tunneling machine adapted to travel on tracks and operated within a tunnel and 15 having a wide range of adjustment, whereby the tunnel is excavated and the material thus excavated carried back and deposited in rear of the machine into cars thus avoiding the extra handling of the excavated material.

20 Another object of my invention is to provide a tunneling machine of the scoop form which can be readily dumped and conveyed back to cars on the same track as that supports the tunneling machine.

25 Another object of my invention is to provide a more effective tunneling machine of this character having certain details of construction and combination of parts herein 30 after more fully set forth.

In the accompanying drawings:

Figure 1 is a side elevation of my improved tunneling machine operating within a tunnel. Fig. 2 is a top plan view of Fig. 35 1. Fig. 3 is an end view showing the shovel and its operating mechanism and the movable supporting frame. Fig. 4 is a side view of the shovel showing the bottom releasing mechanism.

40 1 represents the railroad track within the tunnel 2, as is ordinarily used in such work, and is intended to be of the same gage as that used in the transporting of the material in the tunnel by train cars. My improved tunneling machine is portable upon such track and, when at work at the face of the tunnel, is designed to rest upon the terminus of the track and may be advanced or withdrawn upon same as necessity requires.

45 3 represents the chassis of the device mounted upon suitable wheels 4 and which pivotally carries at 5 the main frame of the machine. This frame may be constructed of wood or metal, as desired, and may either 50 be a skeleton frame or completely housed in, as necessity requires. I have illustrated it as

an open construction, comprising a bottom 6 and sides 7—7, properly braced and united in any desired manner suitable for the purpose.

60 The forward end of the frame is supported upon a plurality of suitable wheels or rollers 8, which rest upon a track on the platform 9 of the chassis 3 and which will permit of the forward end of the frame being moved from side to side of the tunnel to facilitate the working of the shovel. This lateral movement may be accomplished by power being applied to one or more of the rollers 8, as indicated at the centermost one 65 of such rollers in dotted line, Fig. 2, and which may be controlled or operated in any desired manner.

70 The upper edges of the sides 7—7 of the frame incline downwardly toward the front and carry intermediate their uppermost side walls the longitudinally reciprocal platform 10 which is supported upon suitable axles 11, preferably one adjacent each end thereof, and said axles are mounted upon wheels or 75 rollers 12, one upon each end of each axle, which rest upon the side walls 7 within elongated cut-away apertures 13 formed for the purpose within the side walls, as clearly seen in Figs. 1 and 3 of the drawings, thus the 80 platform 10 is capable of reciprocating longitudinally. In order to provide for such reciprocating movement of the platform 10, I have shown mounted upon the same at 85 each side thereof a rack bar 14, each of which is engaged by a suitable pinion 15 mounted upon the transverse shaft 16, said shaft being journaled within suitable bearings 17—17 mounted upon the uppermost edges of the side walls 7—7 of the frame 90 and deriving its power in any suitable manner, such as a sprocket chain and wheels, as indicated, from the power unit 18, located within the body of the frame.

95 It is not considered necessary to complicate this application by illustrating a precise mechanism for alternately operating the shaft 16 at will, as such devices are well known and accomplished in numerous ways, and it suffices to say that reciprocal control of the platform 10 is brought, in any convenient manner, within ready reach of the operator, and, while I have illustrated the rack and gear attachment for this purpose it is readily understood that a system 105 of air cylinders might be applied for the purpose, with possibly equal results.

Upon the forward end of the platform 10 is securely fixed a strong pivotal hinge, 11, the free end of which carries an adjustable strap 20 which encircles the shovel cylinder 21. The strap 20 is made adjustable in that it is formed of two parts, the free ends of which are held together by means of an adjustable bolt 22 and nut 23, as clearly seen in Fig. 3 of the drawings. By this means the cylinder may be adjusted vertically and fixed to suit the work in hand. Within the cylinder 21 is the reciprocal piston 24, the piston rod 25 of which protrudes through the lower end of the cylinder and forms the operating arm proper of the shovel 26 and by which the latter is controlled vertically. The operation of the piston within the cylinder is performed by the application of air which may be led to the cylinder by means of a suitable arrangement of a flexible hose, as indicated at 27, or any other preferred arrangement known to the art, whereby the operator has full control of the vertical movement of the shovel.

Auxiliary guiding rods 28-28 are attached to the rear wall of the shovel 26, one upon either side of the piston rod 25 and which trend parallel therewith and pass through guiding eyes 29-29 formed integral with the head 30 of the cylinder 21. Guiding eyes 31-31 are formed integral with the annular flanged ring 32 which is fixed to the cylinder 21 practically intermediate its ends and above the holding strap 20, which further guide the rods 28-28 as they are moved therein.

Lines 33-33 are attached to the extreme upper ends of the rods 28-28 by means of eyes and extend longitudinally the cylinder 10 to the upper end thereof where they pass through the pulleys 34-34, suspended from the upper end of the cylinder head, and from thence down over the pulleys 35-35 attached to the upper surface of the moving platform 10, thence to the double winding drum 36, mounted upon the shaft 37 which is journaled within suitable boxes 38-38 fixed to the upper edge of the side walls 7-7 of the stationary frame carried by platform 9.

The shaft 37 is designed to run continuously and derives its power from the unit 18 in any desired manner, such as by means of wheels and sprocket chains, as illustrated. Means for intermittently controlling the revolution of the drum 36 is provided for by means of the clutch 39, which slidably engages the toothed end of the drum, as clearly illustrated in Fig. 2 of the drawings, the clutch being controlled by a system of levers, 40, 41 and 42, and the shaft 43, which latter leads to a readily accessible point for the operator of the device which, for convenience is determined to be the left-hand corner of the frame of the machine, approxi-

mately at A, Fig. 2. By this arrangement the cylinder 21 may be operated at will and it is readily seen that no power is necessary to cause it and the shovel to assume the position shown in Fig. 1 of the drawing, as its own weight being suspended as it is, will bring about this result automatically and power is only required to bring the shovel into working action, except that the rack and pinion mechanism 14 and 15 may be used to properly position the platform 10 to cause the shovel to engage the end of the tunnel.

When the shovel is in position as shown in Fig. 1, draft upon the lines 33-33 will cause it to traverse the face of the tunnel in the path of an arc of a circle, until, such time as the cylinder 21 assumes a position parallel with the platform 10 and resting thereupon, a suitable saddle 44, being provided for the purpose, provided however that the shovel, during such travel, does not meet with sufficient resistance to prevent such travel.

If abnormal resistance does occur and the oscillating motion of the cylinder 21 thereby stopped, a continued stress upon the lines 33-33 will cause the shovel to be raised in its relation to the cylinder and thus force the piston 24 upward into the cylinder and thus reduce the bite of the shovel until it becomes sufficiently free to allow the cylinder to resume its oscillation.

If air under pressure is admitted into the cylinder above the piston this relief action may be retarded or prevented entirely if desired to force the shovel to its work or, on the other hand, if additional relief to the shovel is desired, air may be admitted into the cylinder below the piston and such readily afforded, or the platform 10 may be advanced or withdrawn by means of the racks and pinions before described or allowed free action as the work demands, thus it is seen that perfect adjustment and control of the shovel are instantly available, while under normal circumstances it automatically adjusts itself to the work.

Assuming the shovel to have filled with material and draft upon the lines 33-33 sufficient to bring the cylinder 21 down parallel with the platform 10, and such draft be continued, the platform, cylinder, shovel and load will be drawn toward the drum 36 by the action of the lines winding thereupon and which may be assisted through the medium of the rack and pinion, if desired. In operation this draft is continued until the shovel comes directly over the apron 45 of the receiving pocket, when the fixed stops 46-46 will engage the pins 47-47 on the door dogs 48-48 and force the dogs to disengage the latch pins 49-49 of the shovel door 50 and allow it to drop by gravity, which it will quickly do, and result in the

instant discharge of the contents of the shovel into the pocket and onto the conveyer belt 51 by which it is carried longitudinally the machine and discharged at the rear end into tram car 56 prearranged for the purpose.

The conveyer belt 51 is designed to be kept running continuously by suitable power transmission connection with the power unit 10 18, which may be by means of sprocket chains 51' and wheels as illustrated, or any other suitable form of transmission.

The dogs 48 are pivotally mounted upon the sides of the shovel, as at 52 and are 15 formed with counterbalancing ends 53, which, when the shovel is lowered into action, will drop down and engage pins 54 for sustaining them while they hold the door 50 closed, by the latch pins 49 being engaged 20 in the mouth 55 of the dogs.

The power unit 18, illustrated in the drawing, is electric, and, as readily understood, may be controlled from any predetermined position on the machine and I have 25 illustrated a controlling lever 57 as leading to the desired point of control.

A compressed air power unit may be employed instead of electricity without departing from the invention.

30 Having thus fully described my invention what I claim and desire to secure by Letters Patent is:

1. A tunneling machine comprising a frame, an endless conveyer carried by the frame and extending beyond the rear end of the support, a longitudinally movable member carried by the frame, means for moving said member, a cylinder intermediately pivoted to the outer end of the longitudinally movable member, a piston rod carried by the cylinder, a shovel carried by the lower end of the piston rod, guide rods connected to the shovel and extending along the side of the cylinder, cables connected to the said guide rods and extending over pulleys carried by the upper end of the cylinder, means carried by the frame for operating said cable, and means for automatically dumping the shovel when the longitudinally movable frame is moved rearwardly.

2. A tunneling machine of the character described, comprising a frame, an endless conveyer carried by the frame and extending beyond the rear end of the frame, a longitudinally movable member carried by the upper end of the frame, means for moving said member on the frame, a cylinder intermediately pivoted to the outer end of the longitudinally movable member, a piston within the cylinder, a piston rod carried by the piston, a shovel carried by the lower end of the piston rod, rods connected to the shovel and extending through guides carried by the sides of the cylinder, cables connected to the upper ends of the guide rods,

pulleys carried by the upper end of the cylinder and over which the said cables pass, and means carried by the frame for operating said cables, whereby the cylinder is caused to rock upon the longitudinally movable member, and means for automatically dumping the shovel by the rearward movement of the longitudinally movable member.

3. A tunneling machine comprising a frame, an endless conveyer carried by the frame and extending beyond the rear end thereof, a longitudinally movable member carried by the upper end of the frame, means for moving said member longitudinally, a cylinder intermediately pivoted to the outer end of the longitudinally movable member, a piston within the cylinder, a piston rod carried by the piston, a shovel carried by the outer end of the piston rod, a pivoted bottom carried by the shovel, a latch for locking the bottom closed, guide rods carried by the shovel and passing through eyes carried by the cylinder, cables connected to the upper end of the guide rods and passing over pulleys carried by the upper ends of the cylinder, means carried by the frame for operating said cables, and means carried by the frame for engaging the latch for releasing the bottom of the shovel when the longitudinally movable member is moved inwardly, whereby the contents of the shovel are discharged upon the endless conveyer.

4. A tunneling machine comprising a frame, an endless conveyer carried by the frame and extending beyond the rear end thereof, a longitudinally movable member carried by the upper end of the frame, a cylinder pivoted to the outer end of said longitudinally movable member, a piston within the cylinder, a piston rod carried by the piston, a shovel carried by the lower end of the piston rod and having a pivoted bottom, a latch for holding the bottom closed, guide rods carried by the shovel and extending through eyes on the side of the cylinder, cables connected to the upper ends of the guide rods and passing over pulleys carried by the upper ends of the cylinder, and means carried by the frame for operating said cables whereby the cylinder is rocked upon the longitudinally movable member and the bottom automatically released by the engagement of lugs carried by the frame when the longitudinally movable member is moved inwardly, whereby the contents of the shovel are discharged upon the endless conveyer.

5. A tunneling machine comprising a frame, an endless conveyer carried by the frame and extending beyond the rear end of the frame, a longitudinally movable member carried by the frame, a cylinder pivoted to the outer end of said member, a piston rod carried by the cylinder, a shovel rigidly carried by the lower end of the piston rod

and having a pivoted bottom, a latch for holding the bottom closed, rods carried by the shovel and extending up parallel to the sides of the cylinder and passing through guides, cables secured to the upper ends of the rods and passing over pulleys carried by the upper end of the cylinder and extending to a drum on the frame, and a motor carried by the frame for operating the rollers, the

endless conveyer and the drum, substantially as shown and described.

In testimony whereof I hereunto affix my signature in the presence of two witnesses.

SAMUEL HOAR.
